UNITED STATES PATENT OFFICE.

JOHN MÜLLER, OF KANSAS CITY, MISSOURI.

COMBINED SQUARE, MITER, AND BEVEL.

SPECIFICATION forming part of Letters Patent No. 319,012, dated June 2, 1885.

Application filed January 27, 1885. (No model.)

To all whom it may concern:

Be it known that I, JOHN MÜLLER, a citizen of the United States, residing at Kansas City, in the county of Jackson and State of Missouri, have invented a new and useful Improvement in Combined Square, Miter, and Bevel, of which the following is a specification, reference being had to the accompanying drawings.

10 My invention relates to a combined folding square, miter, and bevel, and it has for its object to provide a device of this character which shall be cheap and simple in its construction, effective in its operation, and one 15 that will be strong and durable.

With these ends in view the invention consists in the improved construction and combinations of parts hereinafter fully described, and pointed out in the claims.

20 In the drawings, Figure 1 is a plan view of a combined folding square, miter, and bevel. Fig. 2 is a plan view showing the device folded. Fig. 3 is a section on the line xx of Fig. 2, and Fig. 4 is a detail view of the blade removed. Figs. 5 and 6 are detail views of plates B B' and set-screw G, respectively, the view of plate B' being taken from the under side thereof.

In the accompanying drawings, in which 30 like letters of reference indicate corresponding parts in all the figures, A represents the blade, which is, as usual, provided with a series of graduated marks, a . The inner end of the blade A is provided with a head, A', 35 having a hole or opening, e , at equal distances from which are arranged a series of downwardly-extending pins, d .

B B' represent the end pieces of the square. The under end piece, B, is provided with a 40 threaded opening, e , near one end, and surrounding said threaded opening is a series of perforations or openings, f , arranged in a circle, as shown. The upper piece, B', is provided with an opening, C, near its end, and 45 in a line with the threaded opening of the lower plate, B. The said opening C is surrounded by a countersink or depression, E. The under plate, B, is provided with a plate, F, which may be formed integral therewith or secured thereto. The plate B' is provided

with downwardly-extending pins a^2 , which are adapted to engage recesses a^3 , formed in the plate F, and securing plates B B' together. It will be seen that by providing this plate a space is left between the two plates B B' to 55 allow the ready turning of the blade A therein.

G represents a set-screw for clamping the blade between the plates B B'. The said set-screw is formed with a finger-piece, g , which 60 is adapted to fit in the countersink or depression in the top plate, B', and with a flange, h , which flange h fits the opening in the top plate, the threaded portion of the set-screw passing through the opening in the blade and 65 engaging the threaded opening of the lower plate, the downwardly-extending pins on said blade engaging any four of the series of openings in the said blade.

It will be seen that by loosening the set-screw sufficiently to allow the pins to be removed from the lower plate the blade may be turned to any desired angle, and by engaging the pins with the openings and tightening the set-screw the said blade will be held 70 securely in place.

The blade may be folded between the plates, as shown, and when in such position its inward movement will be limited by the supplemental plate by which the space is formed 80 between the plates B B'.

The above-described device is simple in its construction, effective in its operation, may be manufactured and supplied at a slight cost, and by its use adjustments of the blade to different angles may be almost instantly obtained, and the blade, when so adjusted, will be held firmly in position.

Having fully described my invention, what I claim as new, and desire to secure by Letters Patent, is—

1. In a combined square, miter, and bevel, the combination, with plates, of a blade pivoted between the same, downwardly-extending pins on said blade, openings in the lower plate to receive the same, and a supplemental plate between the plates B B', as set forth. 95

2. In a combined square, miter, and bevel, the combination, with the plates B B', the plate B having a series of openings and a 100

screw-threaded opening, as shown, the plate B' having an opening surrounded by a countersink, of a blade having downwardly-extending pins, a set-screw having a finger-piece 5 and a collar, and a supplemental plate fitted between the plates B B', as set forth.

In testimony that I claim the foregoing as

my own I have hereto affixed my signature in presence of two witnesses.

JOHN MÜLLER.
